PRIMARY CELL OF THE LEAD-ZINC TYPE

Hyman J. Mandel, Red Bank, N. J., assignor to
the United States of America as represented by
the Secretary of War

Application October 16, 1945, Serial No. 622,649

3 Claims. (Cl. 136—118)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to primary cells.

It is an object of the invention to improve the capacity of primary cells, particularly of that type which utilizes the zinc-sulphuric acid depolarizing cathode system.

The invention accomplishes the mentioned object by providing a cell construction which increases the active surface of the anode, whereby a greater cell capacity is obtained, especially when the cell is under a high current drain. Also, the construction which I have provided, and which is hereinafter disclosed, provides a cell having a steadier voltage, under high current drain, than previous cells operating under the mentioned system. Furthermore, my invention has so improved the zinc-sulphuric acid-lead peroxide cell to such an extent that it is now substantially equivalent to the heavier type heretofore used, viz; the lead-sulphuric acid depolarizing cathode type.

The invention is illustrated in the accompanying drawings, which show

Figure 1 is an elevational view of the lead peroxide plate;

Figure 2 is an elevation of a perforated zinc plate;

Figure 3 is a plan view of Figure 2 folded;

Figure 4 is an elevation of a separator;

Figure 5 is a plan of Figure 4 folded;

Figure 6 is a plan of the elements of the previous figures showing them in their relative positions as first assembled;

Figure 7 is a plan view of the same elements as shown in Figure 6, but in their final form and enclosed by a retaining wrapper; and

Figure 8 is an elevation of Figure 7.

Referring to the drawings for a more detailed description of the invention, Figure 1 shows a plate 10, which constitutes the cathode of the cell, and consists of lead peroxide paste 11 filling the spaces of a lead-antimony grid 12, being the same as the cathode used in the lead-sulphuric acid-lead peroxide type of cell. The plate 10 is provided with a terminal 13 at its upper edge.

Figure 2 shows part of the anode of the cell as a zinc plate 15 which has the same height as, and substantially twice the width of, the plate 10, and is adapted to be folded along the center line 16 as illustrated in Figure 3. It is seen that the plate 15 has perforations 17, the purpose of

which will be explained below, and that it has a terminal 18 on its upper edge.

Figure 4 shows a separator 19 which is of the same height as the plate 10 and separator 15 and has a width substantially four times that of the former plate and twice that of the latter, and is adapted to be folded zig-zag along the lines 20, 21 and 22, as illustrated in Figure 5. The separator may be of any suitable absorbent material, such as blotting paper for example, adapted to absorb and hold the electrolyte of the cell, which is dilute sulphuric acid of specific gravity 1.250.

Figure 6 shows the previously described elements 10, 15 and 19 preliminarily assembled in their relative positions, in which the cathode 10 is disposed in the center fold of the separator, i. e., between the inner surfaces of the two inner sections of the separator. The folded perforated zinc plate 15 fits over the two inner sections of the separator 19 so that its own two sections are each positioned in an outer fold of the separator, i. e., between an outer section and the adjacent inner section of the separator. As also shown in Figure 6, the assembled elements 10, 15 and 19 are disposed within a folded unperforated or solid zinc plate 25 which constitutes part of the anode of the cell, the other part, as pointed out above, being the perforated zinc plate 15. The plate 25 has a terminal 26 on its upper edge and this terminal is soldered to the terminal 18 of the perforated zinc plate 15 so that the latter plate and the solid zinc plate together constitute the anode of the cell.

35 The elements shown in Figure 6 are pressed together as shown in Figure 7, so that the electrolyte-saturated separator 19 contacts both sides of the cathode 10 and also both sides of the perforated zinc plate 15, as well as the inside surface of the solid zinc plate 25. Electrically conductive paths between the cathode and both plates of the anode are therefore provided within the cell, it being evident that the current between the cathode 10 and the perforated zinc plate 15 travels through the inner sections of the separator 19 and that the current between the cathode and the solid zinc plate 25 travels through the inner sections of the separator and through the perforated zinc plate 15 and the outer sections of the separator. It is thus seen that the zinc plate 15 is perforated for the purpose of allowing current to pass from the anode, said perforations containing electrolyte expressed from the separator when the elements of the cell are pressed together into the position

shown in Figure 7, in which position they are held by an enclosing wrapping 28 which is of a non-conducting material not attacked by the dilute sulphuric acid constituting the electrolyte. Such wrapping may be made from a sheet of a suitable synthetic plastic material such, for example, as polystyrene.

I claim:

1. In an electric cell, a depolarizing cathode, an absorbent separator folded zig-zag into four sections and adapted to hold a sulphuric acid electrolyte, a zinc anode comprising two plates one of which is perforated, the other unperforated, each of said plates folded into two sections, said cathode disposed in the middle fold of the separator with both faces contacted thereby, the mentioned perforated zinc plate having each of its sections in an outer fold of the separator with both faces of each section contacted by the separator, said cathode, anode and separator disposed within the fold of the unperforated zinc plate.

2. In an electric cell, a lead-peroxide cathode, an absorbent separator folded zig-zag into four sections and adapted to hold a sulphuric acid electrolyte, a zinc anode comprising two plates one of which is perforated, the other unperforated, each of said plates folded into two sections, said cathode disposed in the middle fold of the separator with both faces contacted thereby, the mentioned perforated zinc plate having each of its sections in an outer fold of the separator with both faces of each section contacted by the

5 separator, said cathode, anode and separator disposed within the fold of the unperforated zinc plate, and retaining means around the cathode, anode and separator to hold these elements in contacting relation.

10 3. In an electric cell, a cathode, an absorbent separator folded zig-zag into four sections and adapted to hold a sulphuric acid electrolyte, an anode comprising two plates one of which is perforated, the other unperforated, each of said plates folded into two sections, said cathode disposed in the middle fold of the separator with both faces contacted thereby, the mentioned perforated plate having each of its sections in an outer fold of the separator with both faces of each section contacted by the separator, said cathode, anode and separator disposed within the fold of the unperforated plate.

HYMAN J. MANDEL.
